PAGE 6

FIG. 6

FIG. 1 is a front view of a restaurant embodying my new design;

FIG. 2 is a side view showing one side thereof;

FIG. 3 is a side view showing the opposite side thereof;

FIG. 4 is a rear view thereof;

FIG. 5 is a top plan view thereof;

FIG. 6 is an enlarged view in perspective of a portion of FIG. 1 showing details of my new design;

FIG. 7 is an enlarged view in perspective of a portion of FIG. 2 with parts broken away showing details of my new design.

I claim:

The ornamental design for a restaurant, substantially as shown.
